MOTOR COMPRESSOR

Raoul Pateras Pescara, Paris, France

Application March 1, 1933, Serial No. 659,221
In Germany March 1, 1932

10 Claims. (Cl. 230—56)

My invention relates to motor compressors of the type in which the compressing pistons are driven directly by the energy derived from the combustion of a fuel.

Compressors of that type comprise at least one pair of opposed pistons adapted to reciprocate freely in a common power cylinder. The mixture of air and fuel is fed into said cylinder between said pistons, where it explodes, while the outer faces of the two pistons serve to compress air in separate compression cylinders. In order to obtain a satisfactory return or inward stroke of the pistons, and to ensure a smooth working of the engine a portion of the energy for the return of the pistons is stored in the form of compressed air in cylinders distinct from the compression cylinders, so as to form compensating air cushions therein.

The chief object of my invention is to provide a motor compressor of that type which can be readily started.

It is known to start motor compressors of that type by injecting air into the compression cylinders thereof. This method necessitates that the pressure in the compressed air reservoir should be at least equal to the maximum pressure in the compression cylinders during the starting of the engine, because if that condition were not fulfilled the air compressed in the compression cylinders would leak into the compressed air reservoir, thus considerably increasing the amount of compressed air necessary for the starting.

According to my invention the engine is started by bringing the pistons close to the end of their outward stroke and then injecting a given quantity of compressed air from a suitable reservoir through a check valve into the compensating air cushion cylinders. The pistons are thus strongly driven toward each other so as to compress the air present in the power cylinder up to a high pressure, thus heating that air to a temperature sufficiently high for igniting the fuel that is injected at about the end of the inward stroke of the pistons.

Another feature of my invention is that the compressed air thus fed into the compensating air cushion cylinders is allowed to partly escape therefrom to the atmosphere at the end of each inward stroke of the pistons if its pressure is then higher than the atmospheric pressure, so that, immediately after the compressor is started, the proper pressure is established and maintained in said compensating air cushion cylinders.

A preferred embodiment of my invention will 55 be hereinafter described with reference to the

accompanying drawing given merely by way of example, and in which:

The figure is a longitudinal sectional view of a motor compressor according to my invention.

As shown in the drawing, two opposed pistons 11 and 12 move with a reciprocating motion on the one hand both in power cylinder 13, and on the other hand each in air compression cylinders 14 and 15 respectively. Said pistons are connected through mechanical means comprising connecting rod 6 and a lever 8 oscillating about a spindle between two positions making between themselves an angle smaller than 360°. Piston 12 controls, at one end of power cylinder 13, the exhaust ports 19, and piston 11 controls, at the other end of 16 said cylinder, inlet ports 20 for the scavenging air. 32 is a device for feeding fuel into the power cylinders.

Pistons 11 and 12 carry, on the side of their compressing faces, inlet valves 21, and during 20 their outward stroke, they compress the air contained in chambers 114 and 115 of cylinders 14 and 15, and discharge it through valves 23 into conduits 22.

On the outer ends of the compression cylinders 25 are fixed stationary pistons 24 and 25 which engage cylinders 26 and 27 provided in the main pistons respectively. Said inner cylinders 26 and 27 are connected, through conduit 28, provided with check valves, with a valve 30 adapted to be 30 rapidly opened and which can either shut off in a fluidtight manner, conduits 28 and 29, or bring them into communication with a compressed air reservoir through passage 31.

When valve 30 is closed, the air contained in 35 cylinders 26 and 27 is alternately compressed and expanded while the machine is working.

When the pistons reach the end of their outward stroke, the air present in cylinders 26 and 27 is compressed same as the air which has remained in chambers 114 and 115 of the air compression cylinders, and pistons 11 and 12 are pushed back toward their inner positions with such an energy as to sufficiently compress the gases contained in the power cylinders in order 45 to produce self ignition of the fuel.

The function of the compensating air cushions is to store in a known way, a part of the energy necessary for the return stroke of the pistons.

The walls of pistons 11 and 12 are provided 50 with ports 35 and 36 respectively, which connect cylinders 26 and 27 with the atmosphere at the end of the inward stroke of pistons 11 and 12, through ports 37 and 38 respectively, provided in the air compression cylinders. 55

The operation of the device according to my invention is as follows:

Pistons 11 and 12 are brought into the position shown in the drawing, that is to say to the end of their outward stroke. Valve 30, which is supposed to be closed, communicates with a compressed air reservoir of a given volume the pressure in which has a determined value. Valve 30 is opened and the compressed air rushes into compensating air cushion cylinders 26 and 27, and pushes the pistons backwards toward the middle part of cylinder 13 with such an energy that the air contained in that cylinder is compressed and reaches a high temperature. The fuel is then injected through 32, the ignition takes place, and the pistons are then pushed outwardly by the combustion of said fuel. The air present in cylinders 26 and 27 is compressed and closes valves 33.

At the end of the outward stroke of pistons 11 and 12, that is when the compressed air that has served to the starting of the engine has expanded in cylinders 26 and 27, these cylinders are brought into communication with the atmosphere through ports 35 and 36, so that the excess of said air is allowed to escape to the atmosphere and the normal conditions of working of the air cushions are established.

Furthermore, these ports 35 and 36 compensate, at the end of each outward stroke of the pistons, for the leaks that may occur past valves 33.

While I have, in the above description disclosed what I deem to be a preferred embodiment of my invention, it should be well understood that I do not wish to be limited thereto as there might be changes made in the arrangement, disposition and form of the parts without departing from the principle of my invention as comprehended within the scope of the appended claims.

What I claim is:

1. A motor compressor comprising in combination a power cylinder, two compression cylinders, two pistons adapted to reciprocate on the one hand both in said power cylinder, and on the other hand each in one of the compression cylinders respectively, a compensating air cushion cylinder provided in each of said pistons, a stationary piston at the outer end of each compression cylinder adapted to engage said last mentioned cylinder respectively, a compressed air reservoir, a conduit extending throughout each of said stationary pistons, a check valve at the inner end of said conduit opening inwardly into said compensating air cushion cylinder, a pipe connecting the outer end of each of said conduits to said reservoir and valve means for controlling simultaneously the inflow of air from said reservoir into said pipes.
2. A motor compressor according to claim 1 further comprising means for connecting the compensating air cushion cylinders with the atmosphere at the end of the inward stroke of the first mentioned pistons.
3. A motor compressor according to claim 1, in which the compensating air cushion cylinders are provided with ports opening into the atmos-

phere and so located as to connect the last mentioned cylinders with the atmosphere at the end of the inward stroke of the first mentioned pistons.

4. In a motor-compressor having a motor piston, a compensating compression cylinder pressure in which tends to move the motor piston in a direction to a position in which it compresses the air with which fuel is to be burned, a source of gas under pressure, means to connect said source to said cylinder, and a check valve in said connecting means to prevent the escape of gas therethrough from the cylinder to said source.

5. In a device as claimed in claim 4, said compression cylinder having openings therein connected to the atmosphere, said openings being uncovered when the motor piston reaches compression position.

6. In a motor-compressor, a motor cylinder, a motor piston slidable in said cylinder, a compensating cylinder and a compression piston one of which is slidable with respect to the other, means to introduce gas under pressure into said compensating cylinder, and means connecting said pistons whereby relative separating movement between said compression piston and said compensating cylinder under the pressure of the gas introduced into the compensating cylinder moves the motor piston to fuel compression position.

7. In a motor-compressor, a motor cylinder, a motor piston slidable in said cylinder, a compensating cylinder and a compression piston one of which is slidable with respect to the other, a reservoir of gas under pressure, means to connect said reservoir to said compensating cylinder, a check valve in said connecting means to prevent the flow of gas from said compensating cylinder to said reservoir, and means connecting said pistons whereby relative separating movement between said compression piston and said compensating cylinder under the pressure of the gas introduced into the compensating cylinder moves the motor piston to fuel compression position.

8. In a device as claimed in claim 6, said compensating cylinder having means to connect it to the atmosphere when said compression piston and compression cylinder complete their relative separating movement.

9. In a motor-compressor having a motor piston, a compensating compression cylinder, pressure in which tends to move the motor piston in a direction to a position in which it compresses the air with which fuel is to be burned, a source of gas under pressure, means to connect said source to said cylinder.

10. In a motor-compressor having a motor piston, a compensating compression cylinder pressure in which tends to move the motor piston in a direction to a position in which it compresses the air with which fuel is to be burned, a source of gas under pressure, means to connect said source to said cylinder, and means in said connecting means to prevent the escape of gas therethrough from the cylinder to said source.
